US0D1113832S

(12) **United States Design Patent** (10) Patent No.: **US D1,113,832 S**
(45) Date of Patent: ** Feb. 17, 2026

(54) **AUDIO CONTROLLER**

(71) Applicant: **GUILLEMOT CORPORATION S.A.**,
Carentoir (FR)

(72) Inventor: **Bertrand Medas**, Tassin-la-Demi-Lune
(FR)

(73) Assignee: **GUILLEMOT CORPORATION S.A.**,
Carentoir (FR)

(**) Term: **15 Years**

(21) Appl. No.: **29/907,434**

(22) Filed: **Jan. 5, 2024**

(30) **Foreign Application Priority Data**

Jul. 7, 2023 (EP) 015027444

(57) **CLAIM**

The ornamental design for an audio controller as shown and described.

DESCRIPTION

FIG. 1 is a front left perspective view of my audio controller.

FIG. 2 is a front elevation thereof.

FIG. 3 is a rear elevation thereof.

FIG. 4 is a left side elevation thereof.

FIG. 5 is a right side elevation thereof.

FIG. 6 is a top plan view thereof; and,

FIG. 7 is a bottom plan view thereof.

The broken lines show portions of the audio controller that form no part of the claimed design.

1 Claim, 6 Drawing Sheets
